(57) **CLAIM**

The ornamental design for a slot lock cribbing block, as is shown and described.

DESCRIPTION

FIG. 1 is a front elevational view of a slot lock cribbing block which, along with other slot lock cribbing blocks, provides a heightened platform for outrigger stabilizers or feet;

FIG. 2 is a rear elevational view of a slot lock cribbing block;

FIG. 3 is a left elevational view of a slot lock cribbing block;
FIG. 4 is a right elevational view of a slot lock cribbing block;

FIG. 5 is a top elevational view of a slot lock cribbing block;
FIG. 6 is a bottom elevational view of a slot lock cribbing block;

FIG. 7 is a top-front perspective view of a slot lock cribbing block;

FIG. 8 is another top-front perspective view of a slot lock cribbing block;

FIG. 9 is a bottom-front perspective view of a slot lock cribbing block;

FIG. 10 is a top-rear perspective view of a slot lock cribbing block;

FIG. 11 is a perspective view of a slot lock cribbing block, the view showing a plurality of slot lock cribbing blocks stacked on top of one another and stacked on top of a base pad and covered by a grip pad; and,

FIG. 12 is a perspective view of a slot lock cribbing block, the view showing an exploded view of a plurality of slot lock cribbing blocks configured to be stacked on top of one another and stacked on top of a base pad and covered by a grip pad.

The dashed lines shown represent the environment and represent unclaimed subject matter and form no part of the claimed design.
